Ronell K. Davis,
By E. B. Whitmore, Atty.

UNITED STATES PATENT OFFICE.

RONELL K. DAVIS, OF DESPATCH, NEW YORK.

DOCUMENT-CABINET.

SPECIFICATION forming part of Letters Patent No. 740,098, dated September 29, 1903.

Application filed November 13, 1902. Serial No. 131,200. (No model.)

To all whom it may concern:

Be it known that I, RONELL K. DAVIS, of Despatch, in the county of Monroe and State of New York, have invented a new and useful Improvement in Document-Cabinets, which improvement is fully set forth in the following specification and shown in the accompanying drawings.

My invention is in general an inclosing case or cabinet for conveniently holding paper blanks or forms—such as law blanks, post-office blanks, sheet-music, pads, or other documents, and similar articles—all of which being distinctly separated and divided and ready at hand.

The main object of this invention is to provide an inclosing case and drawer within it of novel construction for holding paper blanks and forms, a number of the cases with contained drawers being usually placed in vertical series and inclosed in cabinet form.

Other objects and advantages of the invention will be brought out and made to appear in the following specification, reference being had to the accompanying drawings, forming a part thereof, the invention being particularly pointed out in the claims.

Figure 1 is a plan of an inclosing case and contained drawer with its contents, parts broken away to disclose the interior. Fig. 2 is a front end view of the device seen as indicated by arrow 2 in Fig. 1. Fig. 3 is a vertical longitudinal section of parts, taken on the dotted line 3 3 in Fig. 1, parts being shown in various positions by full and dotted lines. Fig. 4 shows in vertical longitudinal section the drawer detached, the section being as on the dotted line 4 4 in Fig. 1, parts being shown in various positions by full and by dotted lines. Fig. 5 is a front view of the inclosing case with the door opened or turned up to show the parts within. Fig. 6, drawn to a smaller scale, shows a number of the inclosing cases assembled in vertical series and inclosed in cabinet form. Fig. 7, drawn to an enlarged scale, better shows the construction of the parts at the rear of the drawer, the back board and the bottom board of the drawer being in vertical section.

A in the drawings is a rectangular or box-shaped inclosing case, preferably of wood, for holding withing it the drawer B. When used

singly, this case is provided with a tight cover a and bottom board b to make the inclosure complete; but if two or more cases are associated, as shown in Fig. 6, the bottom board b of one case may, as a matter of convenience and economy, take the place of the top or cover a of the one beneath it. In case both cover and bottom board be employed, as when 55 an inclosing case and its contents are used singly, the only opening of the case is at c, Fig. 5, in front of the inclosed drawer. This opening is normally closed by a vertical swinging or pendent door or closer d, Figs. 2, 3, and 5, held at its upper edge to the inclosing case by hinges e and controlled by gravity, as shown.

The drawer B, which is normally wholly inclosed in the case A, is open both at the top 70 and at the front, the vertical sides f f being slanted or curved at g at their forward ends adjacent to the door, as shown in Figs. 3 and 4. A pull-knob or handle h is secured to the floor i of the drawer for operating the latter, 75 said handle passing out under the lower edge of the door d and projecting in front thereof, as shown. The drawer holds within it a removable folio C for receiving and holding blanks or other sheets or documents l, above 80 enumerated, in its horizontal recesses or chambers k, Figs. 4 and 5, in flat horizontal piles, as shown. This folio C comprises a bottom part or base-board m, usually of pasteboard, of a size to substantially cover the floor i of 85 the drawer. The board m holds at its rear or inner end a series of transverse thick bars n o p, Figs. 4 and 7, secured rigidly to each other and to the base m. These bars decrease in width from the bottom upward, their forward edges retreating and their rear edges being in a vertical plane and normally touching the rear board r of the drawer. The drawers B are sometimes and for some purposes made broad and divided by longitudinal partitions into apartments for receiving two or more folios C side by side, this being merely a matter of convenience or adaptation to particular use in any given case. With each bar is a thick sheet s, of pasteboard or 90 other suitable material, connected with its bar in a hinge or flexible joint, preferably by means of a strip t, Figs. 1 and 7, of flexible material, as stout fabric or oil-cloth. The

sheets *s* are attached at the upper front corners of the respective bars, so as to swing upward, as shown, their normal positions being horizontal with their upper surfaces and the 5 surfaces of the coacting bar in horizontal planes. These cardboard sheets *s* are as wide as the interior of the drawer *B* (or the apartment of the drawer holding the folio if several are associated in a drawer) and form or define 10 horizontal spaces or chambers *k* beneath them for holding the piles of paper blanks *l*, each cardboard sheet constituting a tilting cover for the blank forms or sheets of paper beneath it. These tilting covers are of the same 15 length from front to rear, on account of which their front edges (and also the chambers *k*) recede from low to high, as shown in Fig. 4, corresponding with the recession of the front edges of the bars *n o p*, above described. This 20 recession of the covers *s* and of the open front of the drawer renders all the paper sheets down to the lowest easily accessible and in convenient reach. The forward projecting ends of the covers *s* are usually provided with sheet- 25 metal label-holders *v*, Figs. 1, 4, and 5, for receiving slips of paper or labels *y* for displaying the titles of the particular blanks immediately beneath each cover. The forward ends of these covers are also preferably 30 notched or cut back at one side, as at *x*, Fig. 1, to in part uncover the heads of the blanks beneath as a further means for enabling the eye to quickly perceive the nature of the blanks in the different apartments beneath 35 the respective covers. These covers *s* are also further provided with loops *w* of fibrous or pliable material in positions to be seized by the thumb and finger for raising the cover for the purpose of extracting a paper as may 40 be required.

The handle *h* for operating the drawer may be of any material and of any form desired, save that its surface turned inward or toward the door *d* is of such form as to smoothly act 45 against the door at its outside lower surface. When the drawer is pulled outward, the rounded edges *g* of its sides *f* press the inner surface of the door *d* and swing it outward, the door being finally raised to the elevated 50 position (shown by dotted lines at *d'* in Fig. 3) when riding or resting upon the straight surfaces *u* of the sides *f*. The drawer being thus drawn out, the folio is brought into full view and its contents readily accessible. When 55 the drawer is subsequently pressed inward to

close it, the door, acting from gravity, will commence to descend or swing downward as soon as the declining parts *g g* of the sides of the drawer present themselves beneath it, and as the drawer is moved farther inward 60 the door will continue to swing downward, following along the inclines *g g*, with its lower edge coming in front of the handle *h*, as shown by dotted lines at *d'*, Fig. 3. The final pressing home of the drawer will cause the handle 65 to fully close the door into the opening *c*, and so hold it in its closed position. Each inclosing case *A*, with its contained drawer *B* and inner folio *C*, is a complete working device by itself and may be used singly where but 70 few different papers are required in a given business; but usually several of these cases are assembled, as shown in Fig. 6, and inclosed in an outer casing or cabinet *D*—as, for instance, when in use at post-offices; for which 75 this invention was originally designed.

What I claim as my invention, and desire to secure by Letters Patent, is—

1. A document-cabinet comprising an inclosing case, a drawer within the case, a folio in the drawer having a base, a series of cross-bars rigidly secured to each other and to the base and of different widths, and a series of covers of equal length secured to the upper front corners of the respective bars by flexible joints to swing upward from a normal horizontal position, substantially as described. 85

2. In a document-cabinet, a drawer having vertical sides curved at their forward ends, a floor to said drawer, a base substantially of the same size as said floor, a series of transverse bars supported one above the other at the rear end of said base, and rigidly secured to each other and to the base and decreasing in width from the bottom upward, a cover connected to each bar by a flexible joint, said covers being of substantially the same length and each provided at its forward end with a loop of flexible material, said bars having their rear edges in vertical plane and normally in contact with the rear board of the drawer, substantially as and for the purpose specified. 95

In witness whereof I have hereunto set my hand, this 10th day of November, 1902, in the presence of two subscribing witnesses.

RONELL K. DAVIS.
